UNITED STATES PATENT OFFICE.

GEORGE C. VAN RODEN, OF PHILADELPHIA, PENNSYLVANIA, ASSIGNOR TO
J. E. CALDWELL & CO., OF SAME PLACE.

DESIGN FOR A BADGE.

SPECIFICATION forming part of Design No. 33,623, dated December 4, 1900.

Application filed June 4, 1900. Serial No. 19,082. Term of patent 14 years.

To all whom it may concern:

Be it known that I, GEORGE C. VAN RODEN, a citizen of the United States, residing in Philadelphia, Pennsylvania, have invented and produced a certain new and original Design for a Badge, of which the following is a specification.

My design for a badge is fully illustrated in the accompanying drawings.

10 The essential feature of the design is the large star, with small stars surrounding it within the recesses between the points, a wreath, and a picture within the wreath on the obverse, and a spread eagle on the reverse.

15 Figure 1 is a view of the obverse of the badge, and Fig. 2 is a view of the reverse.

A is the star-shaped piece, and in between the points of this piece are small stars a. On

the face of this star is a wreath B, encircling 20 a border d of a picture D, representing two soldiers. On the reverse is a spread eagle having a shield, and above the eagle is a scroll, and below the eagle are two branches tied together. On the points of the star-shaped 25 piece are balls, the whole giving the effect clearly illustrated in the drawings.

I claim—

10 The design for a badge as herein described and shown. 30

In testimony whereof I have signed my name to this specification in the presence of two subscribing witnesses.

GEO. C. VAN RODEN.

Witnesses:

WILL. A. BARR,
JOS. H. KLEIN.
